UNITED STATES PATENT OFFICE

EUGENE W. CARUTHERS, OF SECANE, PENNSYLVANIA

FROG TIE PLATE

Application filed March 21, 1930. Serial No. 437,846.

My invention relates to tie plates for use in locations where frog or cross-over structure or the nearness of rails in rail structure prevents the placing of separate tie plates of the usual type.

A purpose of my invention is to provide tie plates adapted to give adequate support throughout the width of a frog or cross-over, or across beneath both rails of rail structure whose proximity prevents the use of separate plates.

A further purpose is to provide tie plates of the same length for widely variant widths at different portions of the length of the structure; such as, for instance, between the parts of a frog of different width.

A further purpose is to place two tie plates side by side on the same tie, each tie plate being adapted to give full width support beneath a wide frog or rail structure and each tie plate being adapted to hook over or form an abutment for one side of a frog or rail flange which rests on the two plates, hooking the respective plates over opposite bottom flanges or against joint plates where these occur.

A further purpose is to retain a frog or crossing against lateral movement and fully and fairly support it across its entire face at minimum cost and without restraint against vertical movement.

A further purpose is to support a rail solidly from the bottom against rocking with or without vertical movement using one tie plate to hold against movement in an outward direction and another tie plate upon the same tie against inward movement using stops merely or hooks as needs of service determine.

Further purposes will appear in the specification and in the claims.

I have elected to illustrated one general form only of my invention, with slight modifications, selecting a form that is practical and efficient in operation and which well illustrates the principles involved.

Figure 1 is a fragmentary top plan view illustrating a frog supported by tie plates embodying a desirable form of my invention.

Figure 2 is a side elevation of the structure in Figure 1.

Figure 3 is an enlarged section taken upon the line 3—3 of Figure 1.

Figure 4 is an enlarged top plan view of one of the tie plates.

Figures 5, 6, 7 and 8 are side elevations of several forms of plates, Figure 7 being fragmentary.

Like numerals refer to like parts in all figures.

Describing in illustration and not in limitation and referring to the drawings:—

In usual railroad practice frogs and cross overs have required special tie plates in order that they may be properly supported and that the tie plates agree in width with the variant widths of the frogs at the points where the ties are located. A similar situation has arisen at the heel ends of switches where the rails have separated, but have not separated far enough to permit the placing of separate tie plates of the normal type.

In all such locations where there is not room for separate insertion of individual tie plates, the number of different special tie plates required has been increased not only by the need of support at different widths of frog or rail spacing, but by the further fact that the placing of the ties is not sufficiently uniform and the variation of the frog (or crossing) width and taper is so great that special tie plates have been required to fit a great many otherwise unnecessary slight variations in frog width. Each tie plate has occupied the entire width of the tie and in order to support against movements in both lateral directions by the same tie plate, the abutments for both sides of the frog or crossing have been carried upon the same plate.

Not only has this required a very considerable number of different sizes of tie plates, but the selection and placing of them has required an undue amount of installation time and care.

I provide cooperating tie plates, preferably but not necessarily used, two at each tie, adapted to be used with equal ease and effectiveness at the successive ties along the length of a frog or crossing, whatever its width.

- 5 My cooperating tie plates do not require any definite width of frog or crossing, firmly fasten both sides of the frog or crossing to the tie, present lateral abutments to both sides of the rail, firmly supporting the rail from movement in either direction along the tie and extend beyond the points of engagement with the frog or crossing to prevent tilting of the structure to the injury of the ties.
- 10 In Figures 1 and 2 I have shown a conventional form of frog made up from rails, filler members and a casting but without any thought of restricting it to a frog of this character as distinguished from a frog made up only of rails and filler members or made up of cast parts in whole or in part, and with knowledge that my invention is applicable not only to composite or separately cast frogs but composite or separately cast crossings or 20 for the support of diverging rails whose spacing or other setting makes it desirable to use tie plates common to both rails.

The application to the rails is also obviously independent of whether the rails be parallel or be spreading as at the heel of a switch.

25 As will be seen in the illustration, the rails 10 and 11 approach each other to a point 12 where a filler member is inserted forming part of the frog. The frog tapers outwardly 30 from 13 to 14, is approximately straight to a point 15 and then tapers outwardly to 16. The right end of the frog terminates in diverging rails 17 and 18.

35 My tie plates are applicable to the entire frog length and to a sufficient distance from the frog for the rails to have diverged to permit separate tie plates to be placed beneath them upon the same tie.

The cross section shown in Figure 3 is a 40 conventional one and is shown for the purpose of completeness only and not with any thought of restricting to the particular arrangement of rails and filler members from which the frog is made up at this point.

45 I place two cooperating duplicate tie plates 19 and 20 under the rail side by side upon each tie 21, the pair of plates desirably having a combined width about equal to that of the tie.

50 Each plate is provided with a flat upper surface 22 giving adequate firm support to the frog and an upwardly directed hook 23, 23' or 23'' near one end directed inwardly and adapted to hook over one flange of the frog, 55 crossing or rail or to form an abutment against a splice bar if there be a joint at this location.

The extensions 24 and 25 beyond the frog support against tilting strains.

60 I also provide each plate with perforations 26 near each end for spikes 27 used in spiking the plate to the tie.

65 The tie plates are fastened side by side on the tie with the hooks engaging the opposite flanges, so that the plates are in different rela-

tive longitudinal positions according to variation in the width between the opposite flanges.

70 Thus at a narrow portion of the structure, each plate has considerable extension at 28 beyond the hook end of the other plate, while, where the structure is of considerable width, each plate may have but little extension beyond the other plate, reaching far enough, however, for easy access to the perforations 75 for spiking the plate to the rail and to support against tilting.

80 Though the hook support for the flange of a frog or crossing may be quite desirable in some locations as preventing the frog or crossing from riding high enough so as not to come down in the same tie plate location, I have discovered that it has the disadvantage of tending to lift the tie plate and hence 85 the tie with the frog or crossing due to the wave motion of the entire track with passage of heavy traffic.

90 I secure the advantage of abutment to prevent side movement and at the same time avoid the possibility of the frog or crossing failing to register with the plate in the same position as before by using a stop 23' shown in Figure 8 which is deliberately made high enough to avoid all possibility of the frog or crossing climbing this abutment. Theoretically the space under the hook could be made high enough so as not to interfere with vertical movement, but this offers serious objection of extending the end of the hook inwardly to a plate where it may interfere with bolts placed through the structure whether, 95 frog crossing or switch heel, giving a material advantage to the stop form shown in Figure 8.

100 My invention is applicable in its broader aspects to any form of abutment, whether it be integral, punched up, as in Figure 5, or riveted as in Figure 6, or welded as in Figure 7. It is not my intention to claim specifically the welded form which is included because it 110 comes within the broader features of my invention.

115 In previous attempts to use tie plates provided with a single hook for each flange, no one has recognized that the extension of these plates to form adequate support for the full width of a frog or crossing would make them applicable to such use and I believe that I am the first to provide a tie plate containing any character of abutment for one side of a frog or crossing and long enough to be applicable throughout structures of this character and that I am the first further to provide for adequate support of any such tie plate beyond the point of engagement of the hook with the structure.

120 I believe myself to be the first also to provide an abutment for a tie plate adapted for such use which is free from inward exten- 125

sion above the flange and yet is high enough to prevent climbing of the abutment.

In referring to frogs and cross-overs I have intended to cover the whole group of structures in which frogs occur, including not only the technical structure but also the use of the frog in crossings, cross-overs, turn-outs and all other structures where the condition of variant width of base of the structure 10 to be supported by the tie plate is found.

In view of my invention and disclosure variations and modifications to meet individual whim or particular need will doubtless become evident to others skilled in the art, 15 to obtain all or part of the benefits of my invention without copying the structure shown, and I, therefore, claim all such in so far as they fall within the reasonable spirit and scope of my invention.

Having thus described my invention, what 20 I claim as new and desire to secure by Letters Patent is:—

1. A plurality of ties, a frog or cross-over having flanges at opposite sides and a plurality of tie plates therefor having the same tie 25 plate length for the different widths of the frog or cross-over and arranged in pairs, one tie plate of each pair having an upwardly and inwardly directed hook engaging one 30 side of the frog or cross-over, extending well beyond the frog or cross-over at both ends and having perforations near opposite ends for fastening the plate to the tie, and the other tie plate of the pair like the first but 35 turned end for end with respect to the first and having its hook engaging the opposite side of the frog or cross-over from that engaged by the hook of the first plate.

2. A frog or cross-over and a plurality of 40 tie plates arranged in pairs, having the same tie plate length for the different widths of the frog or cross-over, each plate of each pair extending completely across beneath the frog or cross-over and apertured for fastening 45 to a tie at each end in the extension beyond the frog or cross-over and adjoining plates having abutments on opposite sides of the frog or cross-over to engage with it and maintain its lateral position, the abutments 50 being substantially free from lateral extensions and high enough to avoid danger of climbing by the frog or cross-over.

3. A frog or cross-over and a plurality of 55 tie plates therefor having the same tie plate length for the different widths of the frog or cross-over and arranged in pairs, the tie plates of each pair supporting the frog or cross-over throughout its entire width and being provided with abutments engaging the 60 edges of the frog or cross-over on opposite sides, one abutment on each tie plate.

EUGENE W. CARUTHERS.
